GLOVE

Lauri A. Wickman, San Francisco, Calif.

Application September 21, 1937, Serial No. 164,889

3 Claims. (Cl. 2—161)

My invention relates to the making of gloves; and the broad object of the invention is to provide a glove having seams so disposed as to afford least interference with a tool or other article gripped by the wearer.

Another object of the invention is to provide a glove especially designed for welders, and having seams so disposed as to avoid crevices where drops of hot metal are likely to catch.

10 A further object of the invention is to provide a glove made of sections which may be blanked from sheet material with minimum waste.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the 20 claims.

Referring to the drawings:

Figure 1 is a side elevational view of the palm side of a hand, for purposes of defining the nomenclature employed in describing the glove.

25 Figure 2 is a plan view showing the blanks or sections from which my glove is made, and illustrating the method of cutting the blanks from a sheet of material with little waste.

Figure 3 is an elevational view looking at the 30 front or palm side of a glove embodying my invention; and

Figure 4 is a similar view showing portions of the glove with the thumb extended.

Figure 5 is a sectional view taken in a plane 35 indicated by the line 5—5 of Figure 3, showing the seam construction.

Figure 6 is a rear elevational view of the glove; and

Figure 7 is a front elevational view of a mit 40 embodying a similar construction.

Figure 8 is a front elevational view showing a modified glove construction.

Figures 9 and 10 are front and back elevational views showing still another modification; and

45 Figure 11 is a plan view showing one-piece finger sections.

Figure 12 is a back elevational view showing a modification of the glove in Figures 9 and 10.

In making gloves for workingmen there are 50 several important considerations from the standpoint of the wearer that are overlooked by the glove manufacturer. For example, absence of seams across the back and along the upper ridge of the hand is important in welders' gloves so that drops of molten metal will roll off in-

stead of catching in crevices formed by seams. In almost all trades, where tools are handled, the absence of seams along the upper edge of the forefinger and adjacent inner edge of the thumb is very important. A tool handle is 5 gripped between these parts and a smooth surface, without seams, is highly desirable. A seamless palm is also important in a worker's glove, especially for choppers and ropers, since the tool handle or rope lies across the palm. My improved glove is characterized by the absence of 10 seams in the parts mentioned; and is further designed to comprise few parts so that cutting and assembling is simplified.

In terms of broad inclusion, the glove of my 15 invention comprises a section extending over a side of the hand and having a portion folded over to form a seamless ridge along an edge of the hand. A section is also provided to extend over the other side of the hand, and is connected to the first section by a seam extending along the latter side. The first section preferably lies on the back side of the hand and preferably has portions extending over the backs of the thumb and forefinger, and portions of the 25 back section are preferably folded over to cover the fronts of the thumb and forefinger; these folds being along the inner edge of the thumb and upper edge of the forefinger to form seamless margins along these edges. The glove portions at each of the fingers are also preferably folded over to form seamless margins along the 30 edges of the fingers.

In greater detail, and referring to the drawings, the glove embodying my invention is best 35 described with reference to the parts of a hand. For purposes of defining terms, a hand is shown in Figure 1 with the "front" or palm side facing out; the opposite side being referred to as the "back." The principal parts of the hand are 40 identified as "palm" 2, "thumb" 3, "forefinger" 4, "middle finger" 5, "ring finger" 6 and "little finger" 7. "Upper edge" 8 of the hand is that edge lying above the palm when the hand is positioned as shown; and "upper edge" 9 of the 45 forefinger is a continuation of edge 8. "Lower edge" 11 of the hand is that edge lying below the palm when the hand is positioned as shown; and "lower edge" 12 of the little finger is a continuation of edge 11. The edges between the 50 fingers are called "inner edges"; and the edge 13 of the thumb is also called the "inner edge." Edge 14 of the thumb is called its "outer edge." The sides of the fingers facing out in Figure 1 are called the "fronts," and the opposite sides 55

are called the "backs." The side of the thumb facing out in Figure 1 is the "back," and the opposite side is the "front." Those portions of the fingers and thumb adjoining the palm are referred to as the "base"; and the points between the fingers adjacent their bases are called "junctions."

Now referring to Figure 2, the glove of my invention is formed from sections or blanks cut 10 from a parent sheet 16 of any suitable material, such as leather. The back section of the glove comprises a body portion 17 of generally rectangular shape for extending over the back of the hand, and has a tab 18 projecting from one 15 side. This tab extends over the back of the thumb. A somewhat smaller tab 19 projects from the top side of the thumb tab 18, and is separated from the other portions of the glove by a cut having an outer straight portion 21 20 and an inner curved portion 22. This latter tab folds over to cover the front of the thumb.

Another tab 23 projects from the top of body portion 17 to extend over the back of the forefinger, and a smaller tab 24 is formed alongside 25 to fold over and cover the front of the forefinger. A V-shaped notch 26 is cut in at the base of finger tab 23 to allow portions of this tab to be turned in along the inner side of the finger. A tab 27 also projects from the top of body portion 30 17 for extending over the back of the little finger. A V-shaped notch 28 is also cut in at the base of this tab to permit portions of the tab to be turned in along the inner side of the finger.

The front section of the glove comprises a body 35 section 29 for extending over the palm of the hand, and having three outwardly projecting tabs 31, 32 and 33, adapted to extend over the backs of the little finger, ring finger and middle finger, respectively. A triangular tab 34 projects 40 from one side of the body section, and is bounded by a curved edge 36 and an irregular edge 37 terminating at the base of middle finger tab 33.

Two other finger sections 38 and 39 are also 45 provided for extending over the backs of the ring and middle fingers, respectively. These sections may be separate and cut out between the front and back sections, as shown in Figure 2, with a minimum of waste material.

The assembled glove is shown in Figures 3 to 50 6. In forming the glove the front and back sections are first stitched together along the seam 41 which extends across the lower portions of the thumb to the junction between the middle and forefingers. Sections 38 and 39 of the ring and 55 middle fingers are then stitched at their bases to the back section along the seams 42 and 43. See Figure 6. The front and back sections are then folded together to bring the finger tabs into register; portions of the back section being folded 60 over in this operation to form a seamless ridge 44 along the upper edges 8 and 9 of the hand and forefinger.

The fingers and lower edge of the glove are then stitched together by a seam 46 running from 65 the tip of the forefinger to the lower end of the palm. In making this seam it is to be noted that tabs at the backs of the fingers are pulled forward over the edges of the fingers to form seamless margins along these edges. Likewise portions of the rear section are folded over to form 70 a seamless ridge along the lower edges 11 and 12 of the hand and little finger. Seam 46 thus faces the front side of the glove and leaves smooth the portions between the fingers and along the lower 75 edge of the hand. Figure 5 clearly shows how

the back section 17 is folded over to form the seamless ridge 47 along the lower edge of the hand.

The next step comprises stitching on the cuff 48, if a separate cuff is employed. Finally, the thumb and cuff are closed by stitches along a seam 49. The thumb is formed by folding tab 19 over tab 18, this fold being along the inner edge 13 of the thumb to provide a seamless margin along this edge. As was the case with the 10 other fingers, the back tab 18 is pulled in over the outer edge of the thumb, so that seam 49 lies in front, leaving the edge smooth. Of course the stitching is done with the glove in reverse, so that the stitches are inside, as shown in Figure 15 5. The latter figure also shows the preferred form of seam, including a spacer strip 51. As shown in Figure 6, the short seams at the bases of finger sections 38 and 39 may be covered by a piece 52 stitched to the finger sections and to 20 back section 17.

The above description relates to a five-fingered glove, but the term "glove" as used herein is not limited to such, but also includes gloves having less than five fingers, such as mitts. Figure 7 shows a mitt having a separate thumb and forefinger. This construction is very similar to the glove first described, as comparison of Figures 7 and 4 will disclose. There are just two sections in this mitt since the separate finger sections are unnecessary, the middle, ring and little fingers being held by the mitt portion 53.

Figure 8 shows a modified form of glove construction, in which a tab 54 for covering the front of the middle finger is also formed on the back section instead of the front section. A separate section 56 is provided for the front of the thumb, and is stitched to the front section by a seam 57. Seam 58 extends completely around the thumb and terminates at the junction between the middle and ring fingers. While this construction still has the advantage of a seamless ridge along the upper edges of the palm and forefinger, it does have a seam adjacent the inner edge of the thumb. An extra thumb piece is also required in this construction.

In both types of gloves shown in Figures 3 and 8, the finger sections 38 and 39 may be formed as a single piece, as shown in Figure 11. The advantage of cutting these sections in separate pieces was of course to permit the economical cutting arrangement shown in Figure 2.

Figures 9 and 10 show another modified construction, which is somewhat similar to the form 55 in Figure 3, but in reverse; that is, the thumb and forefinger tabs are formed on the front section instead of the back section. In this case the back section is made in two pieces 61 and 62 connected by a seam 63. The back section is folded over to provide a seamless ridge 64 as before. This back section also has three tabs 66, 67 and 68 for extending over the backs of the little, ring and middle fingers.

Front section 69 carries the thumb tab and also a tab 71 folded over to cover the back of the thumb. A tab 72 is also provided on the front section for extending over the forefinger, and a tab 73 is folded back to cover the back of the 70 forefinger. These folds are along the inner edge of the thumb and upper edge of the forefinger, to form seamless margins along these edges. Front and back sections are connected by a seam 74 across the lower back portions of the thumb and 75

extending around the back of the hand to the junction between the middle and forefingers.

Front section 69 also carries a tab 76 for covering the front of the little finger, and has stitched thereto finger sections 77 and 78 for covering the fronts of the ring and middle fingers; these sections being connected to the front section along seams 79 and 81. The glove is closed by a seam 82 extending from the tip of the forefinger, about 5 the fingers, and then along the lower edge of the glove. In this seaming it will be noted that the front section and the front finger tabs are folded in over the edges of the fingers and the lower edge of the hand to provide smooth seamless 10 margins along these edges. This seam faces the back side of the glove, as shown in Figure 10.

In assembling the glove the front section 69 is first joined to piece 62 of the back section along seam 74, then the two pieces 61 and 62 of the 15 rear section are connected along seam 63. Next the front finger sections 77 and 78 are stitched to front section 69 along seams 79 and 81, and then the front and back sections are joined by seam 82. Finally the thumb is closed by a seam 25 83 extending from the tip of the thumb to the cuff edge of the glove.

This latter glove is especially suited for choppers and ropers, since there are no seams where the tool handle or rope passes between the thumb 30 and forefinger and across the palm.

These gloves work up very well in leather, but it is understood that other materials, such as canvas, may be employed. When using canvas, the glove shown in Figure 10 may be made 35 with less number of pieces by forming the back and front sections in one piece. In this case the back and front sections are joined integrally along the lower edges of the palm and little finger. This eliminates the portion of seam 82 40 between the tip of the little finger and the cuff.

Such a glove would therefore be formed all in one piece, except for the small finger sections 77 and 78. Figure 12 shows the back of such a glove; the front of course being the same as that shown in Figure 9.

I claim:

1. A glove comprising a section extending over the back of the hand, a tab integral with said section and extending over the back of the thumb and having a portion folded over to cover the 10 front of the thumb, the fold being along the inner edge of the thumb to form a seamless margin along said edge.

2. A glove comprising a section extending over one side of the hand, a tab integral with said section and extending over a side of the thumb and having a portion folded over to cover the other side of the thumb, said fold being along the inner edge of the thumb to form a seamless margin along said edge, the portions of the thumb 20 tab being connected together by a seam along the outer edge of the thumb, and a section extending over the other side of the hand and connected to said folded over portion by a seam originating at said edge seam and extending transversely across the thumb to the junction between the forefinger and middle finger.

3. A glove comprising a section extending over the back side of the hand, a tab integral with said section and extending over the back side 30 of the thumb and having a portion folded over to cover the front side of the thumb, the portions of the thumb tab being connected together by a seam along the outer edge of the thumb, and a section extending over the palm side of the hand and connected to said folded over portion by a seam originating at said edge seam and extending transversely across the thumb to the junction between the forefinger and middle finger.

LAURI A. WICKMAN. 40
